United States Patent

Des. 235,808
Patented July 8, 1975

235,808

CRYOGENIC FREEZER OR SIMILAR ARTICLE

Lyle L. Cann, Peotone, Ill., assignor to Chemetron
Corporation, Chicago, Ill.

Filed Feb. 9, 1973, Ser. No. 331,122

Term of patent 14 years

Int. Cl. D15—07

U.S. Cl. D67—2 R

FIG. 1

FIG. 2

FIG. 5

FIG. 3

FIG. 4

FIG. 1 is an isometric view of a cryogenic freezer showing my new design;

FIG. 2 is an end elevation as seen from the left of FIG. 1;

FIG. 3 is a top plan view thereof;

FIG. 4 is an elevational view thereof; and

FIG. 5 is an end elevation as seen from the right of FIG. 1.

I-claim:

The ornamental design for a cryogenic freezer or similar article, as shown.
